[57] CLAIM

The ornamental design for an adaptor for a video camera, as shown and described.

DESCRIPTION

FIG. 1 is a perspective view of a first embodiment of an adaptor for a video camera showing my new design;
FIG. 2 is a top plan view thereof;
FIG. 3 is a left side elevational view thereof;
FIG. 4 is a front elevational view thereof;
FIG. 5 is a bottom plan view thereof;
FIG. 6 is a right side elevational view thereof;
FIG. 7 is a rear elevational view thereof; and,
FIG. 8 is a reference perspective view thereof, the cord portion in broken lines is for illustrative purpose only and forms no part of claimed design.
